UNITED STATES PATENT OFFICE.

ASA R. PURDY, OF BOUND BROOK, NEW JERSEY, ASSIGNOR TO RUBEROID CO., A CORPORATION OF NEW JERSEY.

PREPARED ROOFING ELEMENT.

Application filed December 3, 1921. Serial No. 519,684.

To all whom it may concern:

Be it known that I, ASA R. PURDY, a citizen of the United States, residing at Bound-brook, in the county of Somerset and State of New Jersey, have invented a certain new and useful Improvement in a Prepared Roofing Element, of which the following is a specification.

This invention relates to improvements in prepared roofing elements of the kind that when laid in overlapped courses simulate the appearance of a shingled or tiled roof having spaces between its laterally adjacent shingles or tiles.

15 The objects of the invention are to provide elements that are self-spacing when laid side by side in a row to form a course, that will provide gauges or guides for lapsing successive overlying courses in such 20 manner as to expose a predetermined extent of the surface of the elements of each underlying course, and that can be cut from a piece of prepared roofing material without waste.

25 With these and other objects in view my invention consists in the novel features hereinafter described.

In the accompanying drawings, illustrating a preferred embodiment of the invention;

Figure 1 is a plan view of a portion of a roof laid with my improved elements.

Figure 2 is a plan view of one of the elements, and

35 Figure 3 is a view of a portion of a web or sheet of prepared roofing material having the lines for cutting the elements indicated thereon.

Referring to the drawings, 1 indicates a 40 substantially rectangular shaped element composed of prepared roofing material having parallel straight upper and lower edges 2, 3, and parallel straight sides 4 and 5. A substantially right angled shoulder or projection 6 extends outward from one of the sides, as the side 5, a distance equal to the extent that the sides 4 and 5, respectively, of laterally adjacent elements are to be spaced when laid as shown in Fig. 1.

50 The base of the shoulder 6 extends parallel to the lower straight edge 3 of the element and is positioned vertically therefrom a distance equal to the desired extent of exposure of the element when partly lapped by a similar element. The bases of the

shoulders of the elements of the underlying course accordingly provide a gauge or guide for properly laying the immediate overlying course.

The distance, measured along the side 5, 60 between the upper edge 2 and the top of the shoulder 6 is such that if added to the distance, similarly measured, between the base of the shoulder and the lower edge 3 would be substantially equal to one half of the 65 vertical dimension of the element 1. The vertical dimension of the shoulder itself is also equal to one half of the vertical dimension of the element.

These proportions constitute one of the 70 characteristic features of the invention that distinguish it from the prior art.

In practice I prefer to employ elements measuring 8 by 10 inches, exclusive of the shoulder, laid with 4 inches exposed to the 75 weather and $\frac{1}{2}$ inch apart. In this case the shoulder itself will be $\frac{1}{2}$ by 5 inches, its base will be 4 inches up from the lower edge and its top will be 1 inch down from the upper edge. It is to be understood, of course, that 80 the dimensions of the element may be varied. For example, elements measuring 8 by 12 inches, exclusive of the shoulder, and laid 4 inches to the weather may be used. In that case the shoulder will be 6 inches 85 long and it will be positioned 2 inches down from the upper edge. In any case the position and proportions of the shoulder, with respect to the vertical dimension of the element, will remain approximately constant. 90 Elements having these characteristics may be conveniently cut from a web of prepared roofing material without any waste other than that resulting from the partly formed elements produced at the ends of the web at the start and finish of the cutting operation.

In manufacturing the elements I prefer to employ a web or sheet of sufficient width to accommodate several of the elements 100 widthwise of the sheet. Preferably, though not necessarily, I use a sheet of sufficient width to accommodate four rows of elements laid out as indicated in Fig. 3. The sheet is cut lengthwise into four strips of 105 equal over-all widths by means of a median straight line 7 extending parallel to the longitudinal edges of the sheet and two mutually similar broken lines 8 and 9, one on each side of the median line. The bro- 110

ken lines are each equally distant from the median line and the proximate longitudinal edge of the sheet, and are of such character as to leave alternate extensions, which 5 form the shoulders 6 of the completed elements, at each side of the cut. As seen in Fig. 3, it will be noted that the broken lines are slightly offset with relation to each other, the amount of the offset being double 10 the distance from the top of the shoulders 6 to the upper edge 2 of the completed element.

The strips thus formed are each cut transversely at equi-distant intervals by parallel 15 straight lines 10 to divide them into elements of desired lengths. The distance between succeeding parallel lines 10 being equal to twice the length of one of the extensions. The lines 10 each intersect one or the other 20 of the broken lines 8 or 9 at a point intermediate successive extensions on either side of said broken lines respectively to form completed elements each having an extension or shoulder positioned, and of the 25 portions, as hereinabove described.

What I claim is:

1. A self-spacing prepared roofing element having substantially parallel straight sides one of which has a shoulder extending therefrom, the base of the shoulder being spaced from the lower end of the element a distance equal to the extent that the ele- 30

ment is intended to be exposed when laid in overlapping relation with similar elements, the top of the shoulder being spaced 35 from the upper end of the element a distance that added to the distance of the base of the shoulder from the lower end of the element equals one half of the length of the element. 40

2. A self-spacing prepared roofing element having substantially parallel straight sides with a shoulder projecting from one side intermediate the ends, the shoulder being spaced from the lower end a distance defining the length to be exposed when the element is laid, the length of the shoulder being one-half the length of the element. 45

3. A self-spacing prepared roofing element of rectangular shape having a shoulder extending from one of its sides, the length of the shoulder being equal to one half of the length of the element, the base of the shoulder being parallel to the lower end of the element and being spaced therefrom a distance equal to the extent that the element is to be exposed when laid in overlapping relation with similar elements, the top of the shoulder being spaced from the upper end of the element a distance that added to the distance of the base of the shoulder from the lower end of the element equals one half of the length of the element. 55

ASA R. PURDY.
